Howard C. Thompson
ATTORNEY

UNITED STATES PATENT OFFICE.

GEORGE MERLE, SR., OF BROOKLYN, NEW YORK.

VARIABLE CONDENSER.

Application filed April 10, 1925. Serial No. 22,014.

This invention relates to variable condensers and particularly to devices of this class adapted for use in connection with radio apparatus or circuits; and the object of the 5 invention is to provide a device of the class specified which is composed of a stationary unit comprising a plurality of condenser plates which extend entirely around the circumference of an axis in any desired peripheral form to the disks, that is to say, the disks may be round or angular, and also the provision of a plurality of movable plate units 10 cooperatively engaging the stationary unit, the latter units being substantially semi-circular 15 in form or extending about an axis to substantially the extent of 180 degrees; a further object being to provide one means for actuating all of the movable units to adjust them relatively to the stationary unit in a 20 single operation or movement of said means; a further object being to provide means for moving separately and independently the movable units into inoperative position whereby said operating means may operate 25 one or more as well as all of said movable units; a further object being to provide a vernier adjustment for said single operative means; a further object being to provide a device of the class described which is of unitary 30 construction, means being provided for placing all of the movable condenser units in common circuit and with means for placing the stationary unit in independent circuit; and with these and other objects in view, the invention consists in a device of the class and for the purpose specified, which is simple in construction and operation, efficient in use 35 and which is constructed as hereinafter described and claimed.

The invention is fully disclosed in the following specification, of which the accompanying drawing forms a part, in which the separate parts of my improvement are designated by suitable reference characters in each 40 of the views, and in which:

Fig. 1 is a face view of my improved condenser mounted upon a panel with parts of the construction broken away and in section.

Fig. 2 is a section on the line 2—2 of Fig. 1.

Fig. 3 is a face view of the back of the condenser.

Fig. 4 is a detail view, on a reduced scale, of one of the plates of the stationary unit shown in Figs. 1 and 2; and,

Fig. 5 is a view similar to Fig. 4 but showing a plate of different form.

In the construction shown, I employ two frame members 10 and 11 preferably composed of insulating material such as hard rubber, bakelite and the like, and these members 60 are of the general form illustrated in Fig. 3 of the drawing, wherein the member 11 is shown in plan, and mounted in a sleeve bearing or bushing 12 centrally of and between said members 10 and 11 is a shaft 13 which projects forwardly beyond the member 10 and is adapted to extend through the panel 14 of a radio receiving set; and secured to the shaft 13 outwardly of the panel is a rotatable graduated dial 15. Secured to said shaft inwardly of the panel 14 and outwardly of the member 10 is a small gear 16 and a large gear 17 rotated by the dial 15 and the shaft 13.

Mounted upon the bearing 12 between the members 10 and 11 is a stationary condenser unit 18 comprising a plurality of thin metallic plates 19, seven of which are employed in the construction shown. These plates are square or substantially square in form as shown in Figs. 1 and 4 of the drawing but 80 may be round in form as seen in Fig. 5 of the drawing. A terminal 20 is provided on the inner end of the bearing 12 to permit of the attachment of a circuit wire therewith as will be apparent.

In the construction shown, four other shafts 21 are mounted in connection with the members 10 and 11 and project forwardly beyond the member 10 and extend through the panel 13 and are provided at their front 90 end portions with enlarged heads or caps 22, one of which is shown in Fig. 2 of the drawing, and mounted on the projecting end portions of the shafts 21 are sleeves 23 which are movable longitudinally thereof and 95 locked in engagement with the shafts 21 by pins 24 operating in bayonet apertures 25 in the sleeves 23. The sleeves 23 are provided at their outer ends with knobs or heads 26 to facilitate the operation thereof and springs 27 are employed between the caps 22 of the shafts 21 and the sleeves 23 to place the parts under tension.

Mounted in connection with the sleeves 23 between the panel 14 and the member 10 are gears 28 larger than the gear 16 and adapted to mesh therewith when in the position shown in Fig. 2 of the drawing but which may be moved out of engagement with the gear 16, separately, by pulling the sleeves 23 outwardly and locking the same in such position by virtue of the bayonet apertures 25.

With this construction, it will be apparent that the gear 16 which is operated through the dial 15 may operate all of the gears 28 or any one of said gears separately or two or 5 more thereof.

Secured to the shafts 21 within the members 10 and 11 are four independent condenser units 29, 30, 31 and 32, each of which is composed of a plurality of metallic plates 33, six 10 of which are employed in each unit, said plates being of the usual form and construction or in other words semi-circular in form, and by keying the gears 28 to the shafts 21 through the pins 24 and apertures 25, the 15 rotation or operation of the separate units 29 to 32 inclusive is controlled and as above stated, when all of the gears 28 mesh with the gear 16, all of said units 29-32 are operated.

The rear ends of the shafts 21 operate in 20 metallic bushings 34 in the member 11 and these bushings project through the rear end of said member and are electrically coupled together by a square conducting plate 35, see Fig. 3 of the drawing, which is mounted 25 on the bushings 34, and a terminal 36 is coupled with one of said bushings to place all of the condenser units 29-32 in circuit.

I have shown a plurality of screws or other attaching devices 37 which extend through 30 the panel 14 and into threaded bushings 38 in the member 10 for holding the condenser device in connection with the panel. I also employ a vernier adjustment member 39 comprising a shaft extending through the panel 35 14 and having a bearing in the member 10, said shaft being provided outwardly of the panel 14 with an operating knob 40 and with a pinion 41 adapted to mesh with the large gear 17 whereby a fine adjustment of the 40 units 29-32 is provided.

From the foregoing it will be apparent that in the operation of my improved condenser, all of the units 29-32 may be rotated relatively to the stationary condenser unit 18 and 45 said units may be adjusted to operate relatively to the stationary unit 18 in the same relative position or may be set or adjusted to have differential relations to said stationary unit as seen in Fig. 1 of the drawing, the 50 adjustments being made by moving the gears 28 out of engagement with the gears 16 and turning said gears and the unit coupled therewith and then again meshing the gear 28 with the gear 16. When it is desired to operate 55 only a part of the units 29-32, those to remain idle will have the gears 28 thereof moved out of engagement with the gear 16 and held in such position by the pins 24 and apertures 25.

With my improved construction, it will be 60 apparent that I provide a variable condenser device which employs a single means or dial for actuating the several movable parts or units thereof, and which by reason of the adjustment and movement of the separate units or 65 the gears 28 thereof I may increase or decrease

the capacity of the condenser at will, and by virtue of my improved construction, the tuning of radio receiving sets is materially simplified in that I have found in practice that when the condenser is adjusted to the desired 70 wave length, further manipulation of the condenser is obviated and the tuning or clarifying of the tone, when necessary, may be accomplished by the other means employed in radio receiving apparatus or circuits. It 75 will be understood that while I have the plates 19 of the stationary unit 18 as rectangular in form in Figs. 1, 2 and 4 of the drawing, same may be round as seen at 19^a in Fig. 5 of the drawing, and it will also be apparent that 80 I am not necessarily limited to the shape of the plate 19-19^a nor am I necessarily limited to the number of these plates employed in any one apparatus, and further, my invention is not limited to the four movable condenser 85 units such as the units 29-32, and various changes in and modifications of the condenser unit construction and arrangement herein shown and described as well as the means for actuating the movable units, may be made 90 within the scope of the appended claims without departing from the spirit of my invention or sacrificing its advantages.

Having fully described my invention, what 95 I claim as new and desire to secure by Letters Patent, is:—

1. A condenser of the class described comprising a stationary condenser unit and a plurality of movable condenser units mounted in cooperative relation with the first 100 named unit, means involving a single operated device normally in engagement with and adapted to actuate said movable units, said last named means involving means for moving one or more of said units out of operative 105 relation with said first named means, said last named means also permitting of the adjustment of the separate movable units into different positions relatively to each other and to the stationary unit. 110

2. A condenser of the class described comprising a stationary condenser unit and a plurality of movable condenser units mounted in cooperative relation with the first named unit, means involving a single operated device 115 normally in engagement with and adapted to actuate said movable units, said last named means involving means for moving one or more of said units out of operative relation with said first named means, said last named means also permitting of the adjustment of the separate movable units into different positions relatively to each other and to the stationary unit, and a vernier adjustment unit for actuating said first named 120 means. 125

3. A condenser of the class described comprising a stationary condenser unit and a plurality of movable condenser units mounted in cooperative relation with the first named 130

unit, means involving a single operated device normally in engagement and adapted to actuate said movable units, said last named means involving means for moving one or 5 more of said units out of operative relation with said first named means, said last named means also permitting of the adjustment of the separate movable units into different positions relatively to each other and to the 10 stationary unit, a vernier adjustment unit for actuating said first named means, and means for placing a circuit in communication with all of said movable units.

4. A condenser of the class described comprising a stationary condenser unit and a plurality of movable condenser units mounted in cooperative relation with the first named unit, means involving a single operated device normally in engagement with and adapted to actuate said movable units, said last named means involving means for moving one or more of said units out of operative relation with said first named means, said last named means also permitting of the adjustment 25 of the separate movable units into different positions relatively to each other and to the stationary unit, a vernier adjustment unit for actuating said first named means, means for placing a circuit in communication 30 with all of said movable units, means for insulating the stationary unit from the movable units, and means for placing the stationary unit in a circuit independent of the first named circuit.

5. A condenser of the class described comprising a stationary condenser unit composed of a plurality of spaced disks of predetermined form and a plurality of rotatable condenser units of substantially the same capacity spaced about the periphery of the first named unit and each of which comprises a plurality of disks adapted to be positioned and movable between the disks of the stationary unit and spaced therefrom, means involving a single dial for actuating all of 40 said movable units, and means for moving the separate movable units into inoperative position with reference to said last named means whereby one or more of said movable units may be actuated by means of said dial.

6. A condenser of the class described comprising a stationary condenser unit composed of a plurality of spaced disks of predetermined form and a plurality of rotatable condenser units of substantially the same capacity spaced about the periphery of the first named unit and each of which comprises a plurality of disks adapted to be positioned and movable between the disks of the stationary unit and spaced therefrom, means involving a single dial for actuating all of 50 said movable units, and means for moving the separate movable units into inoperative position with reference to said last named means whereby one or more of said movable units

may be actuated by means of said dial, and means for providing fine adjustment of said movable units.

7. A condenser of the class described comprising a stationary condenser unit composed of a plurality of spaced plates, the periphery of said plates being divided into a plurality of straight edges and a plurality of movable condenser units of substantially the same capacity positioned centrally of the straight 70 edges of the plates of said stationary unit and each of said movable units comprising a plurality of semi-circular and spaced plates adapted to cooperate with and be positioned between the adjacent portions of the plates 75 of the stationary unit and to be movable into and out of engagement therewith.

8. A condenser of the class described comprising a stationary condenser unit composed of a plurality of spaced plates, the periphery 85 of said plates being divided into a plurality of straight edges and a plurality of movable condenser units of substantially the same capacity positioned centrally of the straight edges of the plates of said stationary unit and each of said movable units comprising a plurality 90 of semi-circular and spaced plates adapted to cooperate with and be positioned between the adjacent portions of the plates of the stationary unit and to be movable into 95 and out of engagement therewith, each of said movable units being provided with a gear and a gear normally meshing with the gears of all of said units whereby the rotation of said last named gear will operate said 100 movable units.

9. A condenser of the class described comprising a stationary condenser unit composed of a plurality of spaced plates, the periphery of said plates being divided into a plurality 105 of straight edges and a plurality of movable condenser units of substantially the same capacity positioned centrally of the straight edges of the plates of said stationary unit and each of said movable units comprising a plurality 110 of semi-circular and spaced plates adapted to cooperate with and be positioned between the adjacent portions of the plates of the stationary unit and to be movable into and out of engagement therewith, each of said 115 movable units being provided with a gear and a gear normally meshing with the gears of all of said units whereby the rotation of said last named gear will operate said movable units, and a graduated dial for actuating 120 the second named gear.

10. A condenser of the class described comprising a stationary condenser unit composed of a plurality of spaced plates, the periphery of said plates being divided into a 125 plurality of straight edges and a plurality of movable condenser units of substantially the same capacity positioned centrally of the straight edges of the plates of said stationary unit and each of said movable units com- 130

prising a plurality of semi-circular and spaced plates adapted to cooperate with and be positioned between the adjacent portions of the plates of the stationary unit and to be movable into and out of engagement therewith, each of said movable units being provided with a gear and a gear adapted to mesh with the gears of all of said units whereby the rotation of said last named gear will operate said movable units, a graduated dial for actuating the second named gear, and means for moving the first named gears independently into and out of engagement with the second named gear in the independent adjustment of said movable condenser units.

11. A condenser of the class described comprising a stationary condenser unit composed of a plurality of spaced plates, the periphery of said plates being divided into a plurality of straight edges and a plurality of movable condenser units of substantially the same capacity positioned centrally of the straight edges of the plates of said stationary unit and each of said movable units comprising a

plurality of semi-circular and spaced plates adapted to cooperate with and be positioned between the adjacent portions of the plates of the stationary unit and to be movable into and out of engagement therewith, each of said movable units being provided with a gear and a gear adapted to mesh with the gears of all of said units whereby the rotation of said last named gear will operate said movable units, a graduated dial for actuating the second named gear, means for moving the first named gears independently into and out of engagement with the second named gear in the independent adjustment of said movable condenser units, and a vernier adjustment for said movable units comprising a large gear rotatable by said dial, a pinion meshing with said gear and means whereby said pinion may be rotated.

In testimony that I claim the foregoing as my invention I have signed my name this 3rd day of April, 1925.

GEORGE MERLE, Sr.
